(Cl. D80—5)

To all whom it may concern:

Be it known that I, Clare E. Hodgman, a citizen of the United States of America, and resident of Mamaroneck, in the county of Westchester and State of New York, have invented a new, original, and ornamental Design for a Combination Display Stand and Box for Finger Rings, of which the following is a specification, reference being had to the accompanying drawing, forming part thereof.

In the drawing:

Figure 1 is a plan view of a combination display stand and box for finger rings with cover closed, showing my new design;

Figure 2 is a side elevational view thereof, with cover open;

Figure 3 is a perspective view thereof with cover open; and
Figure 4 is a sectional view on the line 4—4 of Figure 3.

I claim:

The ornamental design for a combination display stand and box for finger rings, substantially as shown.
